US0D1058310S

(12) **United States Design Patent** (10) **Patent No.:** **US D1,058,310 S**
(45) **Date of Patent:** **** Jan. 21, 2025**

(54) **ROUND BOWL**

(71) Applicant: **Hebei Fenger Intelligent Technology Co., Ltd**, Shijiazhuang (CN)

(72) Inventor: **Jianzhong Zhang**, Handan (CN)

(73) Assignee: **Hebei Fenger Intelligent Technology Co., Ltd**, Shijiazhuang (CN)

(**) Term: **15 Years**

(21) Appl. No.: **29/874,097**

(22) Filed: **Apr. 14, 2023**

(51) LOC (15) Cl. **07-07**

(52) U.S. Cl.

USPC **D7/629**; D7/703

CLAIM

The ornamental design for a round bowl, as shown and described.

DESCRIPTION

FIG. 1 is a first perspective view of a round bowl showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an exploded view of the round bowl thereof. The broken lines shown in the drawings depict portions of the round bowl that form no part of the claimed design.

1 Claim, 9 Drawing Sheets
